Patented May 8, 1917.

Inventor

334 Watson E. Coleman

UNITED STATES PATENT OFFICE.

ROBERT H. McCARTHY, OF MADELIA, MINNESOTA.

GUARD.

1,225,461.

Specification of Letters Patent.

Patented May 8, 1917.

Application filed March 24, 1917. Serial No. 157,197.

To all whom it may concern:

Be it known that I, ROBERT H. McCARTHY, a citizen of the United States, residing at Madelia, in the county of Watonwan and State of Minnesota, have invented certain new and useful Improvements in Guards, of which the following is a specification, reference being had to the accompanying drawings.

10 This invention relates to certain improvements in guards and has relation more particularly to a device of this general character especially designed and adapted for use in connection with ships; and it is an object 15 of the invention to provide a novel and improved device of this general character which serves to protect the ship against injury by torpedoes or the like.

It is also an object of the invention to provide 20 a novel and improved guard adapted to be submerged and which is provided at predetermined intervals with explosive devices which are adapted to explode upon percussion as when struck by a torpedo or 25 the like.

Furthermore it is an object of the invention to provide a novel and improved device of this general character which may be disposed across a harbor entrance or otherwise 30 submerged to afford a protection against submarines.

The invention consists in the details of construction and in the combination and arrangement of the several parts of my invention 35 proved guard whereby certain important advantages are attained and the device is rendered simpler, less expensive and otherwise more convenient and advantageous for use, all as will be hereinafter more fully set forth.

40 The novel features of the invention will hereinafter be definitely claimed.

In order that my invention may be the better understood, I will now proceed to describe 45 the same with reference to the accompanying drawings, wherein—

Figure 1 is a fragmentary view in elevation of a guard constructed in accordance with an embodiment of my invention;

50 Fig. 2 is a fragmentary view in top plan with portions broken away of my improved guard as herein embodied;

Fig. 3 is an enlarged view in elevation of one of the disks as herein employed; and

55 Fig. 4 is a sectional view taken through

the disk as disclosed in Fig. 3 with the torpedo mounted therein shown in elevation.

As herein embodied, my improved guard comprises a plurality of disks 1 preferably formed of hard steel and linked one with the other, as indicated at 2. The disks 1 are arranged in a plurality of vertically spaced horizontal rows and are substantially cylindrical in form and provided with perforate ears 3 with which the link connections 2 are engaged. The guard G also includes a plurality of sections which are substantially rectangular in form and defined by the marginal chains 4.

The adjacent vertical chains of the sections are adapted to be connected one to the other by the steel clevises 5 arranged in predetermined vertically spaced relation. The upper chain 4 of each of the sections is operatively engaged with a float F disposed longitudinally thereof and positioned at either side of the section. Each of the floats F is preferably formed of metal and is provided with a plurality of air chambers or compartments C. By constructing the floats F in this manner it will be perceived that the buoyancy of the float will not be materially effected should a portion thereof be injured by an explosion or from any other cause.

The corresponding faces of the disks 1 or more particularly the outer faces thereof are provided with the pockets 6 in which is adapted to be positioned a torpedo or other explosive medium adapted to explode by percussion. The torpedo or the like is substantially entirely confined within a pocket 6 and is held therein by an annular member 7 overlying an outer face of said torpedo or the like and maintained in applied position by the pliable members 8. Each of the members 8 is disposed through an opening 9 produced in the disk 1 and has its opposite ends hooked, as indicated at 10. One of the hooks 10 is engageable with the annular member or ring 7 while the second hook 100 serves to hold the member in operative engagement with the disk. The member 8 is also pliable so that upon the torpedo or the like being exploded no undue resistance will be offered thereto by the annular member or ring 7.

When my improved guard is adapted to be employed in connection with ships the same may be held in proper position relative to the vessel through the medium of 110

suitable cranes and when the device is adapted to be disposed across a harbor entrance or the like the floats F may be held or anchored in any manner which will best meet the requirements of practice.

From the foregoing description, it is thought to be obvious that a guard constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

1. A guard comprising a plurality of connected disks, a face of each of said disks being provided with a pocket, and an explosive medium arranged within each of the pockets.
2. A guard comprising a plurality of connected disks, a face of each of said disks being provided with a pocket, an explosive medium arranged within each of the pockets, and means for holding said explosive medium within the pocket.
3. A guard comprising a plurality of connected disks, a face of each of said disks being provided with a pocket, an explosive

medium arranged within each of the pockets, and buoyant means coacting with a marginal portion of the connected disks.

4. A guard comprising a plurality of connected disks, a face of each of said disks being provided with a pocket, an explosive medium arranged within each of the pockets, and a member carried by each of the disks and overlying the explosive medium for retaining the same within the pocket. 40

5. A guard comprising a plurality of connected disks, a face of each of said disks being provided with a pocket, an explosive medium arranged within each of the pockets, a member overlying the explosive medium, and detachable means coacting with the member and the disk for holding the member in applied position. 50

6. A guard comprising a plurality of connected disks, a face of each of said disks being provided with a pocket, an explosive medium arranged within each of the pockets, a member overlying the explosive medium, detachable means coacting with the member and the disk for holding the member in applied position, and a pliable member operatively engaged with the first named member and the disk for holding said first named member in applied position. 55

In testimony whereof I hereunto affix my signature in the presence of two witnesses.

ROBERT H. McCARTHY.
